LOAD WEIGHING SYSTEM FOR LIFT TRUCKS AND THE LIKE

Filed Feb. 21, 1951

UNITED STATES PATENT OFFICE

2,643,781

LOAD WEIGHING SYSTEM FOR LIFT
TRUCKS AND THE LIKE

William M. Wise, Detroit, Mich.

Application February 21, 1951, Serial No. 212,124

1 Claim. (Cl. 214—2)

1 This invention relates to hydraulic weighing scales and more particularly to a hydraulic weighing system for installation upon a fork lift truck or the like to enable a load to be weighed at the same time as it is lifted by the truck fork.

The advantages of hydraulic scales are well recognized; namely their high accuracy and sensitivity. Also, in my co-pending applications, Serial Numbers 25,006, filed May 4, 1948, and 139,446, filed February 19, 1950, I have disclosed hydraulic scales of compact and rugged construction and of high accuracy and sensitivity, capable of being incorporated in cranes or hoists to weigh loads as they are lifted.

An important object of the present invention is to extend the usefulness of hydraulic scales, and in particular, the scales as disclosed in my said co-pending applications, by rendering it possible for such scales to be employed in association with the lift fork and boom structure of a conventional lift truck to enable the loads handled by the truck to be weighed at the same time as they are lifted by the boom and fork structure.

Some such lift trucks are provided with hydraulic means for raising the lifting fork, and it has heretofore been proposed that a hydraulic scale or indicator be inserted in the hydraulic lifting system, calibrated in pounds for other units of weight. This proposal was based upon the concept that the hydrostatic pressure in the hydraulic lifting system of such a truck is proportional to the load upon the fork. This concept is roughly true, but due to the inherent character of such trucks, it is necessary that the load always be supported in a position which is far off center with respect to the lifting mechanism. Due to the inherent requirement that the load be located off center, a frictional component is introduced which is so high that the pressure in the hydraulic lifting system does not vary accurately with load variations. Attempts to incorporate hydraulic weighing means in the hydraulic lift mechanisms of such trucks have accordingly failed.

It, therefore, becomes an important object of this invention to provide a fork lift truck having a hydraulic scale which is capable of being actuated in accordance with the weight of a load supported by the lift fork but which scale is not subjected to the deleterious effect of the friction involved in the mounting of the lift fork on the truck boom.

It is also an object of the invention to provide a hydraulic load weighing system for installation on a fork lift truck to weigh the loads handled

by the truck with a high degree of accuracy and sensitivity.

Other objects and advantages of the invention will become apparent upon consideration of the present disclosure in its entirety and with reference to the accompanying drawings in which:

Figure 1 is a side elevational view illustrating a fork lift truck equipped with a hydraulic weighing system in accordance with the invention, the upper portion of the boom being shown broken away for convenience of illustration;

Fig. 2 is an enlarged vertical sectional view on the line 2—2 of Fig. 1 showing the pressure gage and indicator dial assembly, and

Fig. 3 is an enlarged longitudinal sectional view on the line 3—3 of Fig. 1 showing the hydraulic pressure cell employed in this embodiment of the invention.

Referring to the drawings, reference character 10 designates, generally, a fork lift truck having a vertical boom 12 pivotally mounted at its lower end upon the truck structure for swinging movement about a transverse axis in conventional manner and carrying a fork structure, indicated generally at 14.

The fork structure is of conventional L-shape form, as shown, and disposed with the horizontal arm or arms 16 capable of being entered beneath a load to be lifted and transported by the truck, the vertical arm 18 being connected with the boom for movement therewith as well as for vertical movement therealong. Such movement can be arranged to be effected in any known manner, as employed on conventional lift trucks. The means employed for this purpose forms no part of this invention.

According to the invention, the vertical arm 18 of the lift fork is pivotally mounted near its upper end upon a transverse horizontal axis upon a pin 20 carried by a bracket 22 forming part of a slide structure, indicated generally at 23 mounted upon the boom for sliding movement therealong, the slide structure being actuatable in any conventional or suitable manner by the lift mechanism of the truck.

A hydraulic cell, indicated generally at 24 is also carried by and bodily movable with the slide 23. The hydraulic cell 24 (one or more of which may be employed in lateral alignment, as desired) forms part of my hydraulic weighing system and is mounted upon the boom 12 in position so that the lower portion of the lift fork, suspended from the boom by the upper pivot 20, is held-up against the projecting domed nose 26 of a piston 28, slid-

able within a cylinder 30 constituting the cell casing.

It will be seen from Figure 1 that the hydraulic cell 24 is downwardly displaced along the boom with respect to the pivot 20 and is shown in a position corresponding substantially to the point of maximum leverage of the suspended lift fork, although the spacing of the parts is subject to variation. It is intended that the lift fork and hydraulic weighing system should be employed in association with loads of predetermined physical dimensions. By way of example, a standardized bin or stock box is shown in outline at 32, such as is employed in factories, workshops and the like to receive loose articles.

Referring again to the hydraulic cell 24, this is shown in detail in Fig. 3. The piston 28 is held locked in the cylinder 30, at its nose end, by a split retaining ring 34 sprung into an annular groove 36 in the interior of the cylinder. At its opposite end the piston is sealed within the cylinder, with respect to the fluid pressure chamber 38, by a resilient toroidal gasket or so-called O-ring 40 contained in an annular recess 42 in the piston surface. The latter also has another annular recess 44, between the recess 40 and the pressure chamber 38, in which recess 44 an annular series of anti-friction balls 46 are accommodated, and another annular recess 48 adjacent the inside of the lock ring 34, in which recess 48 another annular series of anti-friction balls 50 are accommodated. The two series of balls have a certain degree of axial "play" within their respective annular piston recesses, substantially as and for the purpose described in my said co-pending application Serial Number 139,446. Attached to the end of the cylinder 24 by means of a retaining ring 54 is a rubber-like sealing element 52 bridging the space between and tightly connecting the cylinder and piston. At its opposite end, the cylinder is shown fitted with a disc plate 58, secured to the cylinder end, as by screw-stud means 60, and having an axial conduit 61 opening into the pressure chamber 38 and communicating with a radial conduit 62. This conduit 62 is formed at its outer end to receive, as by a screw threaded union 64, a flexible high pressure hydraulic hose 66. This hose is guidingly supported upon the boom 12 and the truck body structure, as by the clips 68 and extends, in tortuous manner, as seen in Fig. 1, to a conduit 70 which communicates variations of pressure in the pressure chamber 38 to the interior of the Bourdon tube 72 of a Bourdon pressure gage assembly. This assembly, which forms no part of my present invention, is of the same general construction and operation as is disclosed in my said co-pending application No. 139,446, so requires no detail description herein. It is sufficient to state that the mechanism involved includes a dial 74 and pointer 76 fast on a shaft 78, which shaft, and hence the pointer, is rotated from the Bourdon tube in accordance with the variances of pressure communicated to the interior of the Bourdon tube through the conduit 70.

The pressure gage and dial assembly is capable of being mounted as a unit upon the lift truck body, as by screw studs 80, in position, as shown in Figure 1, where the dial is readily visible. A shut-off cock, indicated generally at 82, is shown included in the flexible hose line 84, and is capable of manual operation to render the pressure gage and dial assembly inoperative when the same is not required for use.

When weighing a load on the fork 14 it is neces-

sary that the boom 12 should be vertical. This is insured by the operator arranging that the boom is positioned against a stay or indicating device projecting from the front of the truck and indicated at 84. This may be a flexible blade so that the boom may be moved past the vertical position which it denominates, that is counter-clockwise from the position shown in Fig. 1.

In the use of the invention, and with the cook 10 82 open and the boom 12 held in a vertical position, if, as shown at 32, a standard or predetermined size stock box, crate or other load which has its weight distributed substantially uniformly thereover in a horizontal direction, is supported 15 upon the fork arm 16 with the left hand end of such load, as seen in Figure 1, situated against the lower end of the vertical fork arm 18, pressure resulting from the applied load will be resolved into a pressure exerted axially against the 20 piston 28 to effect a corresponding movement of the scale pointer 76, whereby the load lifted by the fork 14 is weighed and indicated on the dial 74.

The use of standard size stock boxes, bins, carts 25 and the like to hold loose and unsymmetrical parts is quite conventional practice, as well as the use of standard sized packages of sheet material, and other uniform packages, liquid containers and the like. In the use of all such standardized 30 loads with the present invention, the dial 74 would be zeroed to take into account the weight of the box, receptacle, pallet or other tare factor, by rotating the dial 74 by means of the tare setting knob, as more particularly brought out in 35 my last mentioned copending application. It follows, therefore, that the dial can be calibrated to accurately designate the net load.

In some cases it might be desired to weigh 40 loads of different physical proportions upon the same lift truck, as for example, bins or boxes shorter than those of the size indicated at 32. In such event a stop block 86 is provided, shown as rigidly secured to the horizontal fork arm 16, in a position in which the desired centre of gravity 45 relationship will be present if the box is so positioned upon the fork arm 16 that its left-hand end, as seen in Fig. 1, is in contact with this block 86. It will be apparent that such a block could be longitudinally adjustable along the horizontal fork arm 16, as by means of a screw shaft, and that its proper positioning for different sizes of 50 boxes or loads could be calibrated upon the fork arm.

The hydraulic weighing system of this invention 55 can also be employed to weigh a load slung from beneath the fork arm 16 and as indicated at 88 in Fig. 1. To permit this to be done, the fork arm 16 is fitted with a sling block 90, located at a position corresponding to the required position 60 of the centre of gravity and adapted to receive the sling cords 92 in central and balanced relation with respect to the underslung load 88.

While it will be apparent that the embodiment 65 of the invention herein disclosed will fulfill the objects above stated, it will be appreciated that the invention is susceptible to modification, variation and change without departing from the proper scope and fair meaning of the subjoined claim.

70 I claim:

In a load weighing system for lift trucks and the like having a vertical boom, a carriage vertically slidably carried by said boom, and a load supporting fork structure pivoted on and depend- 75 ing from said carriage, hydraulic pressure means

on said carriage and spaced below the pivot means for said fork structure and including a horizontally movable portion for displacing the hydraulic medium, a portion of said fork structure bearing substantially horizontally inwardly against said movable portion of the hydraulic pressure means, and a hydraulic circuit, including indicator mechanism, operatively associated with said hydraulic pressure means so as to indicate the load imposed against said movable member by the said fork structure.

WILLIAM M. WISE.
